(57) CLAIM

The ornamental design for a side seat console, as shown and described.

DESCRIPTION

FIG. 1 is a perspective view of a side seat console showing our new design;

FIG. 2 is a top plan view thereof;

FIG. 3 is a front elevation view thereof;

FIG. 4 is a back elevation view thereof;

FIG. 5 is a right side elevation view thereof; and,

FIG. 6 is a left side elevation view thereof.

The bottom view of this design is not being claimed for any ornamental purposes, and so is not included herein.

1 Claim, 5 Drawing Sheets

FIG. 5
